DESIGN FOR A BASE FOR A DRINK MIXER

Benjamin E. Lawrence, Chicago, Ill.

Application December 18, 1939, Serial No. 88,977

Term of patent 7 years

To all whom it may concern:

Be it known that I, Benjamin E. Lawrence, a citizen of the United States, residing at Chicago, in the county of Cook and State of Illinois, have invented a new, original, and ornamental Design for a Base for a Drink Mixer, of which the following is a specification, reference being had to the accompanying drawing, forming a part thereof.

In the drawing, the single figure is a perspec-

tive view of a base for a drink mixer, showing my design.

The base of the device consists of the upper and lower elements as shown, the upper element being supported on the lower element by three legs.

I claim:

The ornamental design for a base for a drink mixer, substantially as shown and described.

BENJAMIN E. LAWRENCE.
